CLAIM

The ornamental design for a solid cover cap assembly for up top rigid mount orbitor, as shown and described.

DESCRIPTION

FIG. 1 is a top perspective view of a solid cover cap assembly for up top rigid mount orbitor according to the invention;

FIG. 2 is a side view thereof;

FIG. 3 is an opposite side view thereof;

FIG. 4 is a top view thereof;

FIG. 5 is a bottom view thereof;

FIG. 6 is a front view thereof;

FIG. 7 is a rear view thereof; and,

FIG. 8 is a bottom perspective view thereof.

The broken lines in the drawings show portions of the rigid mount orbitor that form no part of the claimed design.

1 Claim, 8 Drawing Sheets
